UNITED STATES PATENT OFFICE.

ALBERT E. JOHNSON, OF BROCKTON, MASSACHUSETTS, ASSIGNOR TO UNITED SHOE MACHINERY COMPANY, OF PATERSON, NEW JERSEY, A CORPORATION OF NEW JERSEY.

MACHINE FOR MAKING INSOLES.

1,089,472.

Specification of Letters Patent. Patented Mar. 10, 1914.

Application filed January 25, 1909. Serial No. 473,993.

To all whom it may concern:

Be it known that I, ALBERT E. JOHNSON, a citizen of the United States, residing at Brockton, in the county of Plymouth and 5 State of Massachusetts, have invented certain new and useful Improvements in Machines for Making Insoles; and I do hereby declare the following to be a full, clear, and exact description of the invention, such as 10 will enable others skilled in the art to which it appertains to make and use the same.

This invention relates to machines for forming insoles and more particularly to machines for forming what are known commercially as "Economy" insoles for use in 15 Goodyear shoes.

After the channel and feather flaps have been cut they are upturned to a position substantially perpendicular to the insole either 20 before or during the operation presently to be described and, in this type of insole, it is desirable that these flaps be secured together while so upturned to properly prepare the insole for the application of reinforcing 25 fabric.

Some difficulty has been experienced heretofore in permanently retaining the upturned channel and feather flaps of Economy, and other insoles of the same general 30 character, in intimate contact so as to form a single compound lip of sufficient strength to receive the stitches for securing the upper and welt in place.

The general object of the present invention 35 is to overcome this difficulty. This object of the invention may be attained by applying to the two upturned flaps a series of fastening devices acting to bind the flaps firmly together. Preferably a line of stitching is em- 40 ployed, and any form of stitch may be used which will hold the separate upturned flaps permanently together.

The particular object of the present invention is to provide suitable means for holding 45 an insole in such relation to the mechanism for inserting the fastenings, for instance, the stitch forming mechanism of a sewing machine, that the fastening device may be properly applied to the upturned flaps. This ob- 50 ject of the invention is accomplished by the provision of an attachment to any conven- ient type of sewing machine, for instance, the National sewing machine (shown in many prior patents, an example being the 55 patent to E. E. Bean, No. 159,144, of Jany.

26, 1875), comprising a suitable sole guide or sole positioning device to bear on the grain side or unchanneled face of the insole constructed and arranged so that when the insole is presented edgewise to the machine with the channel flap resting on the sole supporting table the two upturned flaps will be held, throughout the operation, in proper relation to the stitching mechanism to receive the stitches. 60

Preferably the attachment is mounted on the sewing machine in such a manner that when the sewing machine presser foot is retracted by the operator, to permit the sole to be inserted, the guide or positioning device is also retracted to a position of non-interference with the sole as it is placed in the machine. One way of accomplishing this end is to mount the sole positioning device on the lever by means of which the presser foot is lifted. Means is provided to return this lever, and with it the sole positioning device, to its sole engaging position after control by the operator is released. This means is preferably in the form of a spring. 70 The sole positioning device is thus held yieldingly against the face of the insole, and can, therefore, accommodate itself to any thickness of stock. This construction also permits the sole positioning device to be moved outwardly by any unevenness in the thickness of the sole being operated on as it is fed through the machine. This overcomes 75 any tendency the sole positioning device may have to bind the insole against the edge of the sole supporting table and prevent a proper feeding movement. 80

If desired the sole positioning device may be so constructed and arranged that it is automatically withdrawn from its engagement with the insole during the time the sole is being fed, thus entirely overcoming any friction exerted by the device on the sole. This may be accomplished by so designing the attachment that it will be engaged by 95 one of the moving parts of the sewing mechanism, prior to the commencement of the feeding movement, in a manner to be moved out of engagement with the insole. A convenient moving part which may be utilized to accomplish this result is the lever for lifting the awl, and the support for the sole positioning device may be so designed that, during the latter portion of the movement of this lever, it is engaged thereby and the de- 100 105 110 115

- vice withdrawn from the insole by a movement about the pivot of the presser foot lifting lever as a center. The withdrawal of the sole positioning device from engagement with the insole during the feeding of the sole is not essential, however, for if such device be constructed so as to have an anti-friction bearing on the insole, for instance, if it be made in the form of a roll having its curved surface contacting with the insole, the obstruction offered thereby to the passage of the sole during the feeding movement is negligible and can be disregarded. Neither is it essential that the sole positioning device be so mounted that its removal from working position is under control of the presser foot lifting lever, as obviously this result may be attained by providing other actuating means for this particular purpose.
- 20 To the accomplishment of these objects and such others as may hereinafter appear, as will be readily understood by those skilled in the art, the invention comprises the features and combinations of parts hereinafter described and particularly pointed out in the appended claims.

The preferred form of the invention is illustrated in the accompanying drawing in which—

- 30 Figure 1 is a rear elevation of a National sewing machine with the attachment of this invention applied thereto; Fig. 2 is a side elevation of the parts above the sole supporting table shown in Fig. 1; Fig. 3 is an enlarged detail of the sole supporting table and adjacent parts showing an insole in position to be operated upon; and Fig. 4 is a section, in plan, on the line 4—4 of Fig. 3.

In the embodiment of the invention illustrated in the drawing the stitch forming mechanism, comprising the needle 2, awl 4 and looper 6, and their actuating mechanisms, the presser foot 8 and the actuating mechanism, and the sole feeding mechanism 40 operating through the needle, are all the same as the corresponding parts in the prior patents to E. E. and F. Bean, No. 137,528 of April 8, 1873 and E. E. Bean No. 159,144 of January 26, 1876. Also, as in said prior 45 patents, power for operating these mechanisms is obtained from a belt passing over a pulley 10 on a driving shaft 12.

As is usual, the presser foot is held in its depressed position by a strong leaf spring 14 55 mounted on the frame and bearing on the upper side of a pin 16 projecting from the rear of the presser foot supporting bar. The machine is also provided with the usual lever 18 for lifting the presser foot at the 60 time the sole is inserted in the machine. This lever is fulcrumed at 20 on the frame, has one end extended to a position below the pin 16, and is operated through a treadle (not shown) connected to the lever by a rod 22.

65 In the machine of the prior patents re-

ferred to the end of the lever 18 is normally in contact with the pin 16, but in the machine of the present invention the end of the presser foot lifting lever is held against the frame in a position slightly below the pin 16 by means of a suitably connected light coiled spring 24. This construction holds the lever 18 yieldingly depressed under a light pressure and permits the end of the lever to have a slight play between the frame and pin. The purpose of mounting the presser foot lifting lever in this manner will be presently explained.

The sole supporting table 26 engages the sole at all times and is substantially the same as in the prior patents referred to, with the exception that its upper surface at its outer edge is slightly beveled so as to properly support the upturned flaps of the insole for engagement by the presser foot, as shown in Fig. 3. In order to hold the upturned flaps of the insole in stitch receiving position there is provided a sole positioning device located at the front of and extending above the flap engaging surface of the sole support 80 and arranged to engage the unchanneled face of the insole opposite the flaps. In the illustrated embodiment of the invention this device is shown as an anti-friction member, such as a roll 28 having its curved surface bearing on the insole. The roll is freely rotatable on a support or hanger 30 mounted on any convenient part of the machine. Its location, relative to the sole supporting table, is such that the upturned flaps are properly 90 maintained in working position, in the path of movement of the awl and needle, during the operation of the machine.

As different insoles vary considerably in thickness the roll 28 should be yieldingly 95 mounted to prevent its bearing on the sole with so great a force as to interfere with a proper feed thereof. This may be conveniently provided for by mounting the roll support or hanger on the end of the lever 18 as in this

way, owing to the location of the fulcrum of the lever, the spring 24 can be utilized to provide the desired yield in the sole positioning device. It is for this purpose that the end of the lever 18 is permitted a play 105 beneath the pin 16, as hereinbefore described.

A mounting of the sole positioning device on the presser foot lifting lever is also advantageous in that it provides for a removal of the roll 28 to a position of non-interference 110 with the sole as it is being inserted in the machine, as shown in dotted lines in Fig. 1. It will be obvious, however, to those skilled in the art, that other means may be provided for accomplishing this result. Still another 115 advantage is obtained from a yielding mounting of the sole positioning device. Insoles are not always of the same thickness throughout their length and if the device for bearing on the unchanneled face of the insole were 120

rigidly mounted it is possible that at times, as when in passing the thicker portions, it would bind the sole so hard against the edge of the sole supporting table as to interfere with a proper feed thereof. The yielding mounting of the sole positioning device entirely overcomes this difficulty as the device is permitted to give outwardly as the thicker portions of the insole pass between it and the sole supporting table.

It is sometimes found to be advantageous to provide means for intermittently withdrawing the sole positioning device from working position during the operation of the sole feeding means, thus eliminating all frictional contact between the device and insole at this time. This end may be accomplished by causing the sole positioning device, or its support, to be engaged periodically by one of the moving parts of the sewing mechanism and moved outwardly about the pivot of the lever 18 as a center. The forked lever 23 for operating the awl bar, designated by the same numeral in the patent to E. E. and F. Bean hereinafter referred to, is a convenient moving part, operating in proper time relation to the feeding means, for this purpose. In the illustrated embodiment of the invention the roll support 30 is curved at 31 to provide a clearance space for the reciprocations of the lever 23. This curve may be flattened to such an extent that during the latter portion of the upward stroke of the lever 23, and just before the commencement of the sole feeding movement, the support 30 will be engaged by the lever 23 (see Fig. 2) and the sole positioning device thereby lifted and held away from the insole during the operation of the sole feeding means. The spring 24 will return the sole positioning device to operating position after the lever 23 begins its downward stroke.

The stitching of the upturned flaps starts at one shank and the insole is fed through the machine automatically, being guided by the operator, until the other shank is reached. In this manner the flaps are immediately and positively secured together by a permanent fastening device, thus insuring a retention of both the flaps in upturned position while the reinforcing fabric is being applied and during the stitching of the upper and welt. A dry thread can be used, thus insuring cleanliness of the product and machine. Those skilled in the art will readily recognize the advantage of the use of a positive fastening device over cement, or other adhesive material.

While the particulars of construction herein set forth are well suited to one form of the invention, it is not to be understood that these particulars are essential, since they may be variously modified within the skill of the artisan without departing from the

true scope of the actual invention as defined by the following claims.

What is claimed as new, is:—

1. A machine for securing together the two contiguous upturned flaps of a channeled insole, having, in combination, sole feeding means, a sole support continuously in engagement with one of the flaps and acting to support the insole during the feed, provision for applying to the flaps a series of fastening devices to secure them together and form a single lip, and a device at the front of and extending above the flap engaging surface of the sole support constructed and arranged to bear on the unchanneled face of the insole opposite the flaps and hold the flaps in fastener receiving position on the sole support, substantially as described. 70

2. A machine for securing together the two contiguous upturned flaps on a channeled insole, having, in combination, sole feeding means, a sole support continuously in engagement with one of the flaps and acting to support the insole during the feed, provision for applying to the flaps a series of fastening devices to secure them together and form a single lip, a sole positioning device at the front of and extending above the flap engaging surface of the sole support for engaging the unchanneled face of the insole opposite said flaps, and provision for retracting said device from working position to permit insertion and removal of the sole, substantially as described. 85

3. A machine for securing together the two contiguous upturned flaps of a channeled insole, having, in combination, sole feeding means, a sole support continuously in engagement with one of the flaps and acting to support the insole during the feed, provision for applying to the flaps a series of fastening devices to secure them together and form a single lip, and a yieldingly mounted device in front of and extending above the flap engaging surface of the sole support constructed and arranged to engage the unchanneled face of the insole opposite said flaps and maintain the flaps in fastener receiving position on the sole support, substantially as described. 100

4. A machine for securing together the two contiguous upturned flaps of a channeled insole, having, in combination, sole feeding means, a support for the flaps, provision for securing said flaps together by a line of stitches to form a single, compound lip, and an anti-friction bearing roll at the front of and extending above the flap engaging surface of the sole support for engaging the unchanneled face of the insole, opposite said flaps, with its curved surface to hold the flaps in stitch receiving position on the sole support, substantially as described. 115

5. A sewing machine for securing together 120

the two contiguous upturned flaps of a channeled insole, having, in combination, sole feeding means, a sole support engaging one flap and acting to support the insole during the feed, a presser foot to engage the other flap, and a device at the front of and extending above the flap engaging surface of the sole support constructed and arranged to bear on the unchanneled face of the insole opposite the flaps and hold it with its upturned flaps between the sole support and presser foot in position to receive the stitches, substantially as described.

6. A sewing machine for securing together the two contiguous upturned flaps of a channeled insole, having, in combination, sole feeding means, stitch forming mechanism including a needle, a sole support and a presser foot engaging the flaps said sole support acting to support the insole during the feed, and a yieldingly mounted roll at the front of and extending above the flap engaging surface of the sole support constructed and arranged to bear on the unchanneled face of the insole opposite the flaps and hold the flaps in position for the needle to pass therethrough, substantially as described.

7. A machine for securing together the two contiguous upturned flaps of an insole, having, in combination, a sole support engaging one flap, a presser foot for engaging the other flap, means for inserting a suitable fastening device in said flaps to secure

them together, means for withdrawing the presser foot from working position to permit insertion and removal of the sole, a sole positioning device at the front of and extending above the sole support constructed and arranged to bear on the unchanneled face of the insole opposite said flaps, and suitable connections between the presser foot withdrawing means and sole positioning device whereby when the presser foot is withdrawn from working position the sole positioning device is also withdrawn, substantially as described.

8. A machine for securing together the two contiguous upturned flaps of an insole, having, in combination, a sole support engaging one flap, a presser foot engaging the other flap, means for inserting a fastening device in said flaps to permanently secure them together, a sole positioning device at the front of and extending above the sole support constructed and arranged to bear on the unchanneled face of the insole opposite the flaps, means for feeding the sole, and provision for withdrawing both the presser foot and sole positioning device from working position during the operation of the sole feeding means, substantially as described.

In testimony whereof I affix my signature, in presence of two witnesses.

ALBERT E. JOHNSON.
